UNITED STATES PATENT OFFICE.

SELDEN F. GIBSON AND FRANKLIN M. LAWRENCE, OF PORTLAND, MAINE;
SAID LAWRENCE ASSIGNOR OF HIS RIGHT TO WILLIAM H. STEVENS, OF
SAME PLACE.

STOVE-DOOR KNOB.

SPECIFICATION forming part of Letters Patent No. 349,642, dated September 21, 1886.

Application filed February 17, 1886. Serial No. 192,247. (No model.)

To all whom it may concern:

Be it known that we, SELDEN F. GIBSON and FRANKLIN M. LAWRENCE, both of Portland, in the county of Cumberland and State 5 of Maine, and citizens of the United States, have invented an Improvement in Stove-Door Knobs, of which the following description is sufficient to enable those skilled in the art to which it appertains to construct the same, reference being had to the drawings, herewith 10 made a part of this specification.

Our invention relates to that class of stove-knobs intended to be non-conductors of heat, so constructed that the same will remain sufficiently cool to be handled with the naked hand, even when the body of the stove is very hot; and it consists, more particularly, of a wooden knob with a metal disk-base, having a metal boss or washer upon one side and a countersunk space on the other, with a non-conducting washer, wooden knob, and screw, all as will now be more fully set forth and explained.

The following is a description of our invention sufficient to enable those skilled in the art to construct the same, reference being had to the drawings, making a part hereof.

Our improved knob consists of a metal disk-base of greater diameter than the shank of the wooden knob hereinafter mentioned; but which 30 base may be flat or of such general shape as desired, but having upon the side to which said wooden knob is fixed a circular space countersunk about one-sixteenth of an inch, corresponding in size to the diameter of the shank of said wooden knob, which countersunk space is filled by an asbestos washer or a washer of any other indestructible non-con-

ductor of heat. We do not confine ourselves to the use of a countersunk space in the base, for it may be located in the shank of the wooden 40 knob, or the washer may be used without any countersunk space. Upon the opposite side of the base, if desired, a boss or washer may be added. A wooden knob of suitable size, its shank resting against the non-conducting 45 washer, is attached to the base by means of a screw passing through the center of the device, which screw also serves to attach the device to the stove. The base, when polished or plated, is ornamental, and serves in some degree to 50 shield the knob from the radiated heat, while the asbestos or non-conducting washer and the material of the knob so prevent the absorption of heat that the knob is at all times cool enough to handle with the naked hand.

In the drawings, Figure 1 shows a transverse section of the complete knob; Fig. 2, a perspective view; Fig. 3, the face of the disk-base with the countersunk space.

A is the knob; B, the space for the insertion of the non-conducting washer; C, the disk-base; D, the washer; E, the screw.

We claim—

The combination of a wooden knob with a metal disk-base having a metal boss or washer 65 upon one side and a countersunk space on the other, with a non-conducting washer, wooden knob, and screw, substantially as described and set forth.

SELDEN F. GIBSON.

FRANKLIN M. LAWRENCE.
